[57] **CLAIM**

The ornamental design for the magnetic display type electronic bulletin board system, as shown and described.

DESCRIPTION

FIG. 1 is a front view of the magnetic display electronic bulletin board system according to our design;

FIG. 2 is a view thereof from the right side of FIG. 1;

FIG. 3 is a view thereof from the left side of FIG. 1;

FIG. 4 is a view thereof from the top of FIG. 1;

FIG. 5 is a view thereof from the bottom of FIG. 1;

FIG. 6 is a view thereof from the rear of FIG. 1;

FIG. 7 is a cross sectional view thereof; and,

FIG. 8 is a perspective view thereof illustrating in dashed lines displays mounted thereon, such displays that are shown in broken lines not being part of the design sought to be patented.
